UNITED STATES PATENT OFFICE.

VERNON HEYWOOD STOTT AND LEE SCHOFIELD, OF OLDHAM, ENGLAND.

WATER-HEATER.

1,356,415.

Specification of Letters Patent. Patented Oct. 19, 1920.

Application filed August 6, 1920. Serial No. 401,815.

To all whom it may concern:

Be it known that we, VERNON HEYWOOD STOTT and LEE SCHOFIELD, subjects of the King of Great Britain, residing at Oldham, 5 Lancashire, England, have invented certain new and useful Improvements in Water-Heaters, of which the following is a specification.

This invention relates to water heaters 10 of the kind set forth in the specification of our British Patent No. 20277 of 1914 and in which a float or inverted cup is used for regulating the gas supply, the float is formed with or has attached thereto a lip 15 which projects from the float and contacts with a tappet lever operating a valve which closes or opens a gas supply to the heating burners as the float rises or falls due to the generation of steam or vapor under 20 same.

In the crown of the float a relief hole or valve is provided to allow the steam or vapor to escape.

The object of this invention is to utilize 25 the vapor or steam escaping through the relief hole in the crown of the float for heating purposes with the known automatic control of the gas supply or heating medium at the same time.

30 For the purpose of our invention we lengthen or extend the wall of the float chamber sufficiently high and of a diameter to act as a well for the reception of glue pots, pans, food warming ovens, hot plates, 35 steamers, etc., whose contents require to be heated.

Our invention will be clearly understood 40 from the following description aided by the example shown on the annexed drawings in which—

Figure 1 is a sectional elevation of our invention applied to a glue pot, and Figs. 2, 3 and 4 similar views of our invention applied to a steamer, a food warming oven 45 and a hot plate respectively.

Fig. 5 is a sectional view of sufficient of a heater to illustrate a modification.

We form the float chamber A containing the float or inverted cup B with enlarged 50 and lengthened walls which act as a well C in which is positioned a glue pot D (Fig. 1), ovens E (Fig. 3) or on which can be positioned a steamer F (Fig. 2) or hot plate G (Fig. 4).

55 The well is of sufficient diameter to inclose the regulating finger H from the float

B, which finger H has action on one end of a spindle J, which end is positioned within the well, the spindle passing through a short tube or bearing K, in the wall of 60 the well C and has engagement with the spindle L of the gas regulating valve M the rising or falling of the float A decreasing or increasing the supply of gas to the burner N as will be well understood. 65

In the crown of the float A is the usual relief hole O which admits the steam from under the float A into the well C which becomes filled with steam escaping through the relief opening O of the float A. 70

In this way the necessary heat is transmitted to the contents of the pans while regulation of the gas supply takes place simultaneously.

The steam under the float being closely 75 confined and under slight pressure is necessarily hotter than that escaping from the water in the annulus around the float and the more steam allowed to escape through the relief opening the greater and the 80 quicker the heat performance in the well C.

The volume of steam therefore available for the object in view will be determined by the size of the relief opening O and the size of the float A, the larger the float and 85 relief opening the greater the amount of steam escaping and available for heating in the well C and vice versa.

The float chamber A is of just sufficient size to allow of the free working of the 90 float B and any steam escaping from the annulus around the float B does not serve any useful purpose in regulating the float and is practically negligible for heating in the well C. 95

In addition to its application and use for the purposes mentioned, it may be employed as will be readily understood for heating hot closets, and for ordinary heating purposes within certain limits, and a tap may 100 be fitted as shown in dotted lines Fig. 2 for drawing hot water.

In some cases it may be desirable to increase the heat in the well C beyond that of the steam escaping through the relief opening O and for this purpose the water line could be deep enough to cover a portion of the well extension in which case the tubular bearing K would be made to extend farther into the well above the water line as at 110 Fig. 5 so as to prevent the water escaping through the bearing out of the well.

In cases where the liquid or material only requires to be heated to a comparatively low temperature, only a very small relief hole is needed and sometimes this hole would be so small and fine that it would become blocked up by grit, and in hard water districts it might be that eventually scale deposition would block it up.

As an alternative we employ a larger relief hole O as in Fig. 5 and insert a loose valve piece P which while partially closing up the relief hole O, just allows sufficient space between the periphery of the neck of the valve piece P and the edge of the relief hole O for the requisite amount of steam to escape.

What we do claim as our invention and desire to secure by Letters Patent is:—

1. In combination, a receptacle having a lower chamber adapted to contain a liquid, and an upper chamber in which is positioned an object to be heated, a float in said lower chamber open at the lower end and formed with an aperture at the upper end, a source of heat associated with said lower chamber for heating the liquid therein whereby vapor under pressure may collect under said float and escape through said aperture for heating the object in the upper chamber and means influenced by the vertical portion of said float for controlling the source of heat.

2. In combination, a receptacle having a lower chamber adapted to contain a liquid and an upper chamber for receiving an object to be heated, a float in said liquid of

slightly smaller dimensions than the lower chamber so as to permit the float to move freely therein, said float being provided with a relief opening in its top closure, a source of heat associated with said lower chamber for heating the liquid therein whereby vapor under pressure may collect under the top closure of the float and escape through said opening for heating the object in the upper chamber and means influenced by the vertical position of said float for controlling the source of heat.

3. In a heating receptacle having a chamber for receiving a liquid, and a compartment communicating therewith for receiving an object to be heated, a source of heat for the liquid and a float within said chamber for partially confining the vapor from said liquid, said float having a relief opening formed therein for permitting the escape of vapor under pressure for heating the object in said compartment and means controlled by the position of said float for regulating said source of heat.

In testimony whereof we have hereunto set our hands in presence of two subscribing witnesses.
